Primary Examiner — Karen S Acker(74) Attorney, Agent, or Firm — Ulmer & Berne LLP(57) CLAIM

The ornamental design for a textile with pattern, as shown and described.

DESCRIPTION

The sole FIGURE is a top plan view of the textile with pattern.

In the drawing, the broken lines and the spaces surrounding the solid line perimeter of the claim depict portions of the textile with pattern that form no part of the claimed design.

1 Claim, 1 Drawing Sheet(56)
